UNITED STATES PATENT OFFICE.

CHARLES H. VESTAL, OF ATHENS, TENNESSEE.

DISPENSING MACHINE.

Application filed April 28, 1924. Serial No. 709,611.

This invention relates to combined measuring and dispensing devices, more particularly to devices of this character adapted for measuring and dispensing articles of merchandise which is furnished to the trade in uniformly sized particles, such as sugar, corn meal, dried beans, peas and the like, and has for one of its objects to increase the efficiency and utility of devices of this character.

Another object of the invention is to provide a device of this character including a measuring and dispensing apparatus and an indicating device to denote the quantity and price of the commodity to be dispensed.

With these and other objects in view the invention consists in certain novel features of construction as hereinafter shown and described and then specifically pointed out in the claims, and in the drawings illustrative of the preferred embodiment of the invention—

Figure 1 is a front elevation.

Figure 2 is a side elevation.

Figure 3 is a transverse section, enlarged, on the line 3—3 of Figure 1.

Figure 4 is a transverse section on the line 4—4 of Figure 2.

Figure 5 is a section, enlarged, on the line 5—5 of Figure 2.

Figure 6 is a section, enlarged, on the line 4—4 of Figure 2.

Figure 7 shows, in front elevation, the latching structure shown in Figure 6.

Figure 8 shows, in side elevation, the latching structure shown in Figure 6.

The improved device comprises a container for the commodity to be measured and dispensed and represented as a whole at 10, of any required size of dimensions, but preferably cylindrical in outline, and with an inclined or hopper shaped bottom 11. The container 10 is provided with a transparent panel 12 to disclose the quantity of the contents, and with a detachable closure 13.

Extending from the lower hopper end of the container and communicating therewith is a reduced extension 14 and constituting the receiver for the commodity or material to be measured and dispensed, and corresponding in area to the largest quantity to be measured at one time. The receiver portion 14 is preferably square and merges at

its upper end into the hopper bottom of the container.

The portion 14 is closed at the back and sides with the front and bottom normally open. Slidably disposed over the open front of the receiver 14 is a closure 15, operative in suitable guide devices 16 and more than twice the length of the receiver portion 14, and is pierced about midway of its length to receive a cut off member 17 adapted to extend transversely of the receiver and cut off the flow therethrough.

The receiver 14 is pierced through one side at its lower part to receive another cut off member 18, which constitutes a movable bottom or closure to the otherwise open bottom of the receiver.

Extending from the cut off member 17 is a guide rod 19, the latter slidably supported by a bracket device 20 attached at 21 to the movable closure 15, while the cut off 18 is provided with a similar guide rod 22 slidably supported by a bracket device 23 attached at 24 to the adjacent side of the receiver 14.

Surrounding the rod 19 between the bracket 20 and the cut off 17 is a spring 25 operating to hold the cut off normally and yieldably closed, while a like spring 26 surrounds the rod 22 between the cut off 18 and the bracket 23, and operates to hold the cut off 18 normally and yieldably closed.

Attached at 27 to the closure member 15 is a small bracket 28 having a guide 29 through which a bolt 30 operates and provided with a head 31 having one inclined face, and held yieldably in projected position by a spring 32.

Attached at 33 to the adjacent side of the receiver 14 is a small bracket 34 having a guide 35 through which a bolt 36 is slidably and having a head 37 at one end and with one inclined face as shown, and held yieldably in projected position by a spring 38.

Formed in the adjacent edge of the cut off 17 is a socket to receive the head 31 of the bolt 30, while a similar socket in the cut off 18 receives the head 37 of the bolt 36. By this arrangement when the cut off members 17 and 18 are moved into their outer positions, or transversely of the receiver 14 against the resistance of the springs 32 and 38 by force manually applied to the rods 19 and 22, the heads 31 and 37 will auto-

matically engage the sockets of the cut-offs and retain them yieldably in open position.

Means are provided for alternately withdrawing the bolts 30 and 36, and this means comprises a turning rod 41 supported for rotation at the ends by brackets 42 and 43 attached respectively to the container 10 and the receiver 14, the rod being of other form than round transversely between the brackets 19 as shown in Figures 4, 5, 6 and 7.

Formed in the guide 29 for the bolt 30 is a slot through which a transversely perforated lug 44 extends, and slidable on the rod 41 is a collar 45 having a stud 46 projecting therefrom and passing through the perforation in the lug 44. By this means when the rod 41 is oscillated, the bolt 30 will be forced through the guide 29 and withdraw the head 31 from engagement 20 with the cut-off 17, and release the latter and permit the spring 25 to automatically close the cut-off or dispose it in closed position.

Attached to the rod 41 at its lower end 25 and rotative therewith is a collar 48 having a stud 49 extending therefrom.

Pivoted at 50 on the guide 35 is a bell crank lever 50', pivoted at 50² to the bolt 36, and with a projection 50³ on the other 30 arm extending into the path of the stud 49.

By this arrangement when the rod 41 is oscillated to a certain extent in one direction, the bolt 36 will be moved against the resistance of the spring 38 by the swinging 35 of the bell crank lever and the head 37 thereby withdrawn from its seat in the cut-off 18 to release the same and permit the spring 26 to force it into closed position. Then when the rod 41 is oscillated to a 40 greater extent in the same direction, the head 31 of the bolt 30 will be withdrawn to permit the reaction of the spring 25 to move the cut-off 17 into closed position. At its upper end the rod 41 is provided with a 45 turning crank, having a lug 67 to engage alternately in recesses in a segment 68, one of the recesses being shown at 69. By this means the rod 41 is locked in either one of its two positions.

50 The aperture in the collar 45 which engages the rod 41 is of greater area than the rod as indicated at 52, to provide a certain degree of lost motion to the rod so that the lower cut-off 18 will be released for a sufficient length of time in advance of the release of the upper cut-off 17, to prevent interference between the actions of the cut-off devices as hereafter explained.

Attached to the movable closure 15 and 60 spaced from the guide members 16, are gear racks 53 and 54. Supported at 55 on the container 10 is a stub shaft 56 with a relatively small gear 57 at one end in constant engagement with the rack 54 and with an 65 operating crank 58 at the other end. By

this means the closure 15 is movable vertically between its guides 16 by rotating the shaft 56.

Attached at 59 to the container 10 adjacent to the rack 54 is a stub shaft 60 having 70 a gear 61 at one end in constant engagement with the rack 54.

Attached at 62 to the container 10 adjacent the shaft 60 and through which the latter extends, is a shell 63 having a relatively 75 narrow opening 64 in one side, and mounted on the shaft 60 within the shell is a graduated drum 65. By this means when the shaft 56 is rotated to operate the rack 53 and correspondingly actuate the closure 15, 80 the rack 54 will be moved with the closure 15 and rotate the gear 61 and the drum 65, and the gear 61 being larger than the gear 57, the gear 61 and the drum 65 will be moved at a slower speed than the closure 15.

The receiver 14, as before stated, is designed to contain the greatest quantity of material which it is designed to measure and dispense at one time, and when it is desired 90 to withdraw this greater quantity, the member 15 is moved to its upper position by rotating the crank 58 thus disposing the upper cut-off 17 opposite the upper end of the receiver 14. The cut-off 17 is then drawn into open position by manually drawing the rod 19 outwardly against the resistance of the spring 25, until the head 31 of the bolt 30 snaps into the seat in the edge of the cut-off. At this time the lower cut-off 18 is not 100 disturbed. The material will then flow into the receiver 14 and completely fill the same, and when this is accomplished, the crank 66 is turned to the right to cause the V-shaped edge of the rod 41 to pick up the 105 collar 45 and move it to the right to cause the stud 46 to move the bolt 30 through the head 29 and withdraw the head 31 from its seat in the cut-off 17 and release the latter and cause it to be closed by the reaction 110 of the spring 25. This will cut off the bulk of the material in the hopper and separate the contents of the receiver 14 therefrom. The operating rod 22 of the lower cut-off 18 is then manually operated to draw the 115 lower cut-off into open position against the resistance of the spring 22 and locked in open position by the action of the spring operated lock bolt 36, thus releasing the contents of the receptacle 14.

The lever 66 is then moved to another position to cause the finger 49 to actuate the bell crank lever 50', to withdraw the lock bolt 36 from engagement with the lower cut-off 18 to release the latter and permit it to 125 be moved into closed position by reaction of the spring 22. If a lesser quantity is required to be measured and dispensed, the crank 58 is rotated to adjust the closure 15 in position to locate the cut-off 17 at a 130

point to cut off the desired lesser quantity, which may then be discharged by holding the upper cut-off closed and opening the lower cut-off, as before described.

5 Thus any required portion of the contents of the receiver may be cut off and discharged.

The drum 65 will be provided with gage lines corresponding to the required position of the cut-off 17, and by rotating the shaft 56 until the desired gage line on the drum is visible through the opening 64, the cut-off 17 will be located in position to cut off the required quantity in the receiver.

15 To illustrate. Suppose the commodity to be measured and dispensed is granulated sugar, the surface of the drum 65 will be provided with gage lines divided to represent pounds and multiples or fractions 20 of pounds together with the prices for such quantities. For instance suppose that the receiver 14 is gaged to contain, when full a quantity equal to ten pounds, then if ten pounds is required to be dispensed the closure 15 will be moved to its upper position and the cut-off 17 closed to separate the full contents of the container from the full contents of the receiver. When thus arranged the ten pound graduation on the drum 65 30 will appear opposite the slot 64.

If a lesser quantity is required, for instance five pounds, the lower cut-off is closed and the upper cut-off opened, as before, and the receiver 14 allowed to run full. The crank 58 is then rotated until the cut-off 17 is opposite the middle of the receiver 14, or with five pounds below the line of the upper cut-off, or between the two cut-offs. The upper cut-off 17 is then 40 forced into closed position against the resistance of the spring 25, to separate the bulk of the material in the container and in the receiver above the upper cut-off, and the lower cut-off released by withdrawing 45 the bolt 36-37, and permitting the spring 38 to move it into open position and permitting the material below the upper cut-off to be discharged.

The lower cut-off is then restored to 50 closed position by withdrawing the bolt 36 and permitting the spring 22 to act and the upper cut-off drawn into open position against the resistance of the spring 25 and locked in open position by the spring bolt 55 30, as before described, to permit the receptacle 14 to be again filled.

The receptacle 14 is normally filled, and the upper cut-off 17 manipulated, as above described, to gage the quantity of material 60 to be measured.

Thus it will be obvious that any required quantity may be measured and dispensed by so adjusting the closure 15 that the position of the cut-off 17 corresponds to the

graduation which is visible through the 65 slot 64.

The apparatus can be readily adapted to various commodities or articles by changing the proportions of the receiver 14 and container 10, but without material change 70 in the operation parts.

The improved device is simple in construction, accurate in action, and can be constructed of any desired size or capacity and of any suitable material. 75

What I claim as new is:—

1. A dispensing device of the character set forth comprising, a hopper body having a reduced open fronted lower extension, a vertically slidable panel mounted to move 80 over said open front, means for controlling the vertical movement of said panel, a sliding cutoff extending through said panel and into said extension and movable with the panel, a sliding cutoff mounted upon 85 said extension and adapted to close the lower end thereof, a control spring acting upon each cutoff to normally maintain it in and transversely of the extension, catch means for each cutoff adapted to engage 90 and hold the same in withdrawn position, under proper conditions, and means common to both cutoffs whereby the catches holding the same may be individually manipulated to release them to be acted upon 95 by their respective springs.

2. A dispensing device of the character set forth comprising, a hopper body having a reduced open fronted lower extension, a vertically slidable panel mounted to move 100 over said open front, means for controlling the vertical movement of said panel, a sliding cutoff extending through said panel and into said extension and movable with the panel, a sliding cutoff mounted 105 upon said extension and adapted to close the lower end thereof, a control spring acting upon each cutoff to normally maintain it in cutoff position in the extension, an arm carried by and extending from said panel, 110 a catch carried by said arm designed to engage and hold the cutoff carried by said panel, when the same is drawn outwardly, and release means positioned at one side of said panel and adapted to disengage said 115 catch from said cutoff.

3. A dispensing device of the character set forth comprising, a hopper body having a reduced open fronted lower extension, a vertically slidable panel mounted to move 120 over said open front, means for controlling the vertical movement of said panel, a sliding cutoff extending through said panel and into said extension and movable with the panel, a sliding cutoff mounted upon said 125 extension and adapted to close the lower end thereof, a control spring acting upon each cutoff to normally maintain it in cutoff

position in the extension, an arm carried by and extending from said panel, a catch carried by said arm designed to engage and hold the cutoff carried by said panel, when the same is drawn outwardly, a turnable rod mounted in vertical position adjacent said panel, and an actuating element slideable on said rod and connected between the rod and said catch, designed to retract the catch when the rod is turned to release the cutoff.

4. A dispensing device of the character set forth comprising, a hopper body having a reduced open fronted lower extension, a vertically slideable panel mounted to move over said open front, means for controlling the vertical movement of said panel, a sliding cutoff extending through said panel and into said extension and movable with the panel, a sliding cutoff mounted upon said extension and adapted to close the lower end thereof, a control spring acting upon each cutoff to normally maintain it in cutoff position in the extension, an arm extending from said panel, a sliding catch carried thereby to engage the cutoff carried by said panel when the same is drawn outwardly, an arm mounted adjacent the cutoff carried by said extension, a sliding catch carried thereby for engaging the last mentioned cutoff when the same is drawn outwardly, a vertically mounted turnable rod, means carried at the lower end of said rod for re-

tracting, when turned in a clockwise direction, said last mentioned catch to release the cutoff held thereby, and means slideable on said rod and turnable therewith for releasing, when turned in a counter clockwise direction, the latch engaging the cutoff carried by said panel.

5. A dispensing device of the character set forth comprising, a hopper body having a reduced open fronted lower extension, a panel constituting a closure for said front and mounted to slidably move thereover, a sliding cutoff carried by said panel and extending transversely thereof into and movable in said extension, a sliding cutoff extending across the lower portion of said extension and normally constituting a bottom therefor, a pair of rack elements mounted upon said panel to move therewith, a revolute crank and gear element mounted adjacent one of said elements and connected thereto to raise or lower said panel and the cutoff carried thereby, and means in connection with and actuated by the other rack for indicating the volume of the material contained in said hopper deliverable from said extension by the projection inwardly of the cutoff carried by the panel and the withdrawing of the cutoff closing the lower end of the extension.

In testimony whereof I affix my signature hereto.

CHARLES H. VESTAL.
